(57) **CLAIM**

The ornamental design for a junction for a vacuum circuit and the like, as shown and described.

DESCRIPTION

FIG. 1 is a front, top and left side perspective view of a junction for a vacuum circuit showing our new design;

FIG. 2 is a top plan view thereof;

FIG. 3 is a front elevation view thereof;

FIG. 4 is a left side elevation view thereof, the right side elevation view being identical to the left side; and,

FIG. 5 is a bottom plan view thereof.

The broken line in the figure drawing views are for illustrating the unclaimed environment only and forms no part of the claimed design.
